FIRE CONTROL APPARATUS FOR GUNS

Maurice Kerr Ingolby, deceased, late of Tyne-mouth, England, by Thomas Frederick Clarke, Swanley, England, and Percy William Cole, Purley, England, executors, assignors to Vickers-Armstrongs Limited, London, England, a company of Great Britain

Application February 27, 1945, Serial No. 580,031
In Great Britain October 12, 1937

Section 1, Public Law 690, August 8, 1946
Patent expires October 12, 1958

11 Claims. (Cl. 89—41)

1

This invention relates to a fire or like control apparatus for guns, torpedo-tubes, or similarly controllable devices and is concerned with control apparatus taking into account those relative movements between the gun or the like and the target. For simplicity of language herein use is made of terms such as "guns," "gun transmission," "fire" control apparatus. Although all these terms have a primary application to guns only they are to be considered, if the context permits, as including apparatus where an analogous problem of control arises as, for example, in torpedo discharging gear.

In known prediction apparatus employed for the calculation of adjustments to be imparted to a gun mounting, a sight is employed for following the target, the movements in training and elevation which it is necessary to apply to the sight in order that it should follow the target being communicated to the predictor where such movements are analysed to obtain gun deflections. The analysis of the sight movements which takes place in the predictor must include the determination of the rate of change of the sight movements when the sight is following the target. This may be achieved with the aid of the well-known balance dial constructions, or alternatively, an indicating instrument might be used. An indicating instrument would have the disadvantage that little power would be available for operation of the prediction apparatus, whilst the employment of balance dials necessitates an observer or observers to work at the predictor maintaining the coincidence of the pointers and dials.

It is the aim of the present invention to provide apparatus which will satisfactorily operate in the determination of rates of change of sight elevation and training with the employment of as few observers as possible, so that the fire control apparatus may be mounted upon or within an aeroplane. Following this general requirement it will, of course, be desired to eliminate personnel from the associated gun (or guns), the latter being trained and elevated in a fully automatic fashion. Known gun control apparatus will, in general, either operate with great accuracy but low power or with power sufficient to operate the gun mounting with but a relatively low accuracy. It will, of course, be appreciated that the object of the invention in producing automaticity with great accuracy in the prediction and sighting portion of the control apparatus will be completely defeated if the gun transmission does not also operate with complete automaticity and extreme precision.

2

According to the invention, a fire control system includes an observing sight, a predictor or calculator and gun operating mechanism wherein the movements of the sight in training and elevation are controlled through hydraulic swash-plate pump and motor systems, each such system possessing control means to vary the volume of the supply of the fluid medium with the aid of a valve or by varying the angulation in the swash-plate system, and wherein there are connections from the training and elevating mechanism of the sight to the predictor or calculator so as to introduce into the latter, movements corresponding to the actual training and elevating movements of the sight, there being further connections from said control means to the predictor or calculator so as to introduce also into the latter movements that are proportional to the rate of change of the sight elevating and training adjustments.

According to a further feature of the invention, the output from the calculator or predictor, consisting of corrections in training and elevation to be applied to the associated gun, is magnified by a power amplifier hunter follow-up system comprising a swash-plate hydraulic system with hunter gear.

It may here be mentioned that in previously proposed fire control systems, it is known to employ a sight operating in conjunction with a gun, the elevating and training movements of which are controlled by the motors of hydraulic pump and motor systems. Each pump has a control member which is movable to govern the rate of operation of the associated motor and is, therefore, in its movements proportional to such rate. The sight is carried by the gun and the time of flight is combined with the measured rate just indicated and applied back to the sight to deflect the latter in such manner that the gun should be laid in advance upon a predicted position of a moving target. It may also be mentioned that hydraulic swash-plate systems for remote operation of a gun mounting are known per se.

In order that the said invention may be clearly understood and readily carried into effect, the same will now be more fully described with reference to the accompanying drawings, in which—

Figure 1 is a diagrammatic view of a fire control system according to the invention.

Figure 2 is a sectional view of a detail of the apparatus employed.

Figure 3 is a view similar to Figure 1 of a modified system, and

Figures 4 and 5 are details of the apparatus employed in the system of Figure 3.

Referring now to the drawings, and in particular to Figure 1 thereof, there is an optical range-finding and sighting apparatus 1 of known construction, carried by a mounting 2. Shafts 3 and 4 enter the mounting and respectively control training and elevating of the range-finding device 1. The shafts 3 and 4 are driven from hydraulic swash-plate motors 5 and 6 which have communicating pipes 7 and 8 respectively. The pipes are supplied from hydraulic swash-plate pumps 9 and 10 which are, in turn, respectively driven from sources of mechanical power indicated at 11 and 12. The angulation of the swash-plates of both the pumps 9 and 10 is controllable by means of arms 13 and 14. Each arm is effectively attached to a nut device 15 and 16, the latter working on worm-screws 17 and 18. The worm-screws are respectively carried by shafts 19 and 20, each of which is provided with a controlling handwheel 21 and 22.

Associated with the apparatus so far described there is a calculator or predictor 23 which is intended to derive "future" corrections for an associated gun (or guns) with the aid of certain given "present" values. Amongst the desired "present" values there will be the training and elevating displacements made to the sighting device 1. Measurements of these displacements are obtained from the shafts 3 and 4 with the aid of bevel pinions 23A and 24 associated with shafts 25 and 26. The shaft 25 experiences a movement according to the training adjustment whilst the shaft 26 experiences a movement according to elevation adjustment. There is additionally required for the calculator 23 an accurate estimation of the rate of change of both training and elevation. For reasons that will be indicated more fully hereinafter, a measure of the rate of change of training is obtained upon a shaft 27 that is connected with the shaft 19 through a bevel pinion pair 28. There is also a shaft 29 which connects with the shaft 20 through the bevel pair 30, the shaft 29 affording a measure of rate of elevating. The sighting device 1 is equipped with the usual range-adjusting handwheel 31 and appropriate mechanism 32 from which there is a connection 33 to the calculator or predictor 23 for the purpose of setting therein the "present" range.

From the predictor or calculator 23 there emerge two shafts 34 and 35 and, since the mechanism associated with each shaft is exactly similar, it will suffice to describe only one of such mechanism. The shaft 35, through gears 36 and 37 drives a shaft 38. The latter possesses a non-round part 39 and the gear 37 is slidable thereon having an extended boss 40 which, by means of a bearing 41A, holds the gear 37 in fixed relation to the gear 36 when the shaft 38 is axially displaced. There is a bell-crank 41 arranged at one end to co-operate with a collar 42 supported fixedly on the shaft 38 and arranged to have its other extremity connected by means of a rod 43 with an arm 44, the adjustment of which governs the angulation in a hydraulic swash-plate pump 45. The latter is associated with a swash-plate motor 46, and there is a source of mechanical energy 47 for actuating the pump 45. An output shaft 48 receives the drive from the motor 46 and there is a gearwheel 49 secured upon such shaft. The gearwheel 49 meshes with a gearwheel 50 having an internally screw-threaded boss 51, which engages with external screw-threading 52 upon the 70

shaft 38. The boss 51 has an integral extension carrying a gearwheel 53, whilst the shaft 38 has a non-circular section portion 54 supporting a further gearwheel 55, so that the latter may remain in a relatively stationary position along the axially movable shaft 38. There is means in the form of a bearing boss 150 for maintaining the gearwheel 50 at a fixed location so that if such gearwheel were rotated without there being any rotation of the shaft 38, the latter would be moved axially by virtue of the screw-threading upon the interior of the gearwheel boss 51 and the exterior of the shaft 38. A casing 56 is disposed for angular movement about the shaft 38 and carries a shaft 57 to which there is fixed a pair of pinions 58 which mesh with the gearwheels 53 and 55. A series of teeth indicated at 59 is disposed around the periphery of the casing 56, such teeth being intended to engage with a pinion 60 located on a shaft 61 that returns to the calculator or predictor 23.

The shaft 48 is mechanically connected with a shaft 62 entering a gun-adjusting mechanism 63. The shaft 34 is associated with mechanism 25 precisely similar to that already described and there is an output shaft 64 which likewise enters the gun-adjusting mechanism 63. There is also a return shaft 65 which enters the predictor or calculator 23.

In Figure 2 there is shown, in section, mechanism for elevating and training either the sight 1 or the gun to which the mechanism is to be applied. Thus, the sectional view in Figure 2 may be regarded as a detail of the mechanism 2 or 63. In Figure 2 it will be seen that there is a main central shaft 66 which effects the training adjustment, there being a gearwheel 67 attached to the shaft and meshing with a control worm 68. There is a similar control worm 69 meshing with a toothed annulus 70 which engages with the pinions 71 of an epicyclic gear. A drive from the pinions 71 is taken upon a sleeve 72 which is formed integral with a gearwheel 73, meshing with a further gearwheel 74 which in turn serves to drive a shaft 75 for effecting elevation adjustments. It will be unnecessary to describe the construction of the epicyclic gear in detail and it will suffice to state that there is also a rotatable cage 76 with further planet pinions 77 meshing with a gearwheel 78 upon the shaft 66 and also meshing with a toothed portion 79 on the housing of the mechanism. The epicyclic action permits elevation adjustment of the shaft 75 without disturbance or variation by the training adjustments.

Referring now once more to Figure 1 it will be seen that the shaft 66 of Figure 2 may be regarded as equivalent to the shaft indicated at 80 in connection with the range-finding device 1, whilst the shaft 81 may be regarded as equivalent to the shaft 75. In a similar manner in connection with the gun-adjusting mechanism 63, the shafts 82 and 83 thereof may respectively correspond to the shafts 66 and 75 of the mechanism of Figure 2.

In the use of the apparatus so far described, it will be understood that the range-finding and sighting device 1 will be controlled by visual observation. The observer will be able to adjust the range-finder in elevation and training by means of the handwheels 22 and 21. The range will be set by the handwheel 31 and will be transmitted to the calculator 23. By adjustment of, say, the handwheel 22 it will be understood that a

directly proportional movement will be given to the lever 14 which determines the swash-plate angulation in the hydraulic pump 10. Moreover, movement of the lever 14 is proportional to the speed at which the hydraulic motor 6 will run, given a constant speed for the source of mechanical power 12. If, therefore, the handwheel 22 is being operated so that the shaft 4 keeps the observing sight, i. e., the rangefinder, correctly adjusted in elevation upon the target, then it will be seen that the handwheel 22 is moving in accordance with rate of change of elevation. Such rate of change of elevation is set upon the shaft 29 and into the calculator 23. For obvious reasons, the shaft 26 will move in accordance with the actual elevation adjustment, and for like reasons the shaft 27 will move according to rate of change of training whilst the shaft 25 will move according to actual extent of training. The calculator or predictor 23 deals with these inputs and forms no part of the present invention. Furthermore, the calculator 23 may have other inputs so that there may be derived finally therefrom, gun adjustments in training and elevation upon the output shafts 34 and 35. The mechanism for obtaining power follow-up from the shafts 34 and 35 is identical and only that associated with the shaft 35 need be described. In operation this mechanism functions as a power amplifier with hunter follow-up. When the shaft 35 turns, the movement thereof is communicated to shaft 38 through the gearwheel 37 and due to the threading 52 on the shaft 38 the latter is moved axially. The axial movement produces a swinging of the bell-crank lever 41 which, in turn, adjusts the angulation of the swash-plate in the hydraulic pump 45 by means of the lever 44. On a given adjustment of the lever 44 the motor 46 is set in motion, and there is a drive back from the gear 49 to the gear 50 whereby the screw-threading of the boss 51 carries back, or tends to carry back, the shaft 38 axially towards the position thereof corresponding to a zero setting of the bell-crank lever 41. In a hunter system such as that just described, there will be a certain lag and a correction must be made therefor. For this purpose the shaft 61 is arranged to move in accordance with the extent of lag and drives back into the calculator 23. The movement of the shaft 61 is, at all times, proportional to lag in the hydraulic system for the following reasons. The gearwheel 53 can move only at the same speed as the gear 50 which, in turn, moves according to the speed of the output shaft 48 from the motor 46. On the other hand, the gearwheel 55 must move with the shaft 38. Thus, if the shaft 35 were displaced and, as a result, the shaft 38 similarly displaced, then there would be a lag before rotation of the gear 49 begins and during the period of that lag the gearwheel 55 would be driven whilst the gearwheel 53 would remain stationary. Since both the pinions 58 are fixed upon the shaft 57, the casing 56 must rotate and transmit rotary motion to the shaft 61, proportional to the extent of lag between the input control and output power sides of the hydraulic system.

Referring now to the system shown in Figures 3, 4 and 5, it will be seen that there is in this case also a similar arrangement of a range-finder or sighting device 84 having a control mechanism 85 as shown in Figure 2 of the drawings. As in the previous example, there is an elevation adjusting shaft 86 and a training adjusting shaft 75

87, both of which communicate with the calculator 88 by means of shafts 89 and 90. There are hydraulic swash-plate motors 91 and 92 associated with the shafts 86 and 87 respectively, and there are control handwheels 93 and 94 also associated therewith. In this example, however, the motors 91 and 92 are supplied with pressure fluid from a common pump 95 which receives mechanical energy from the power source 96. There are two pipes 97 and 98 from the pump 95, 98 representing the pressure side and 97 the return. The pipe 97 extends to a T-portion 99, from whence fluid medium is fed back to the pump 95 from valve boxes 100 and 101. Fluid medium is fed from the pipe 98 to the valve boxes by the branch pipes 102 and 103. From each valve box 100, 101, there is a pair of pipes 104, 105 which extends to its associated motor 92, 91 respectively.

In Figure 5 there is shown a detail of a valve box such as indicated at 100 and 101 in Figure 3. The box includes essentially a body member 106 and a valve stem 107 in the extremity of which there is engaged the end of a centrally pivoted lever 108. The other end of such lever is effectively attached to a nut 109 adapted to cooperate with a threaded member 110 upon the shaft 111. There is a hand-wheel upon the shaft so that by the rotation of the latter the valve stem 107 may be made to move axially in either direction.

The valve box body 106 has ports 108A, corresponding to the pipes 104 and 105 and furthermore has a fluid medium inlet 109A and outlet 110A, which may be connected respectively to the pipes 102 and 98, for example. There is a main interior valve chamber 112 which, in this instance, may be of cylindrical form and there is a passageway 113 communicating at either end with the chamber 112 and opening into the outlet 110A. A reversing valve is employed in the chamber 112, the valve possessing portions 114 and 115 which fit within the chamber 112 and which are capable of closing almost completely the ports 108A. From the arrangement of the valve illustrated it will be appreciated that if the valve is moved from the zero central setting in either direction, then depending upon the direction of movement the fluid medium will flow into the inlet 109A and out of one or the other of the ports 108A. That port 108A which does not connect with the inlet 109A, then functions as the exhaust port and permits return fluid medium to pass through the channel 113 to the outlet 110A, thence back to the return side of the central pump of the system. It is important to note that in the valve described the design has to be such that the extent of opening of the valve, by movement of the controlling handwheel, is proportional to the resulting volume of fluid from the outlet side of the valve box, through either of the ports 108A. It is, furthermore, desirable that when the valve is in its zero position, pressure fluid may escape through both the ports 108A to some slight extent in order that the associated motor might be held firmly in a zero position.

Returning now to Figure 3 of the drawings, it will be seen that the handwheel 94 associated with the valve box 100 has a control shaft 116, and that the corresponding handwheel 93 of the valve box 101 has a control shaft 117. Both the shafts 116 and 117 enter the calculator or predictor 88. From the predictor there are emergent shafts 118 and 119 which have set upon them corrections for gun elevation and training. Such corrections are amplified through a power am-

plifier and hunter follow-up system and applied in a gun control mechanism 120, which may be the same as that already indicated in the previous construction. The power amplifier system associated with each correction is identical, and it suffices therefore to describe one in detail. The output shaft 119 is connected by gearing 121 with a shaft 122 which enters lag correction and hunting gear 123. There is an output shaft 124 from the latter which drives back through gearing 125 into the calculator 88. The shaft 124 is arranged to have a movement proportional to the lag in the power amplifier. There is a hydraulic swash-plate motor 125A having an output shaft 126 which enters gun control gear 120.

Figure 4 may be regarded as a detail of the power amplifier system just briefly described and it will be seen that the motor 125A has pipe connections 127 and 128 to a valve box 129 (assumed in Figure 3 to be enclosed in the casing 123 for simplicity of drawing). It will be seen that the construction of the valve box 129 is similar to that shown in Figure 5, except that the valve stem 130 has a yoke end which supports a cam-follower 131. There is, as before, a fluid medium inlet 132 which is intended to be connected to the pipe 133 (see Figure 3). There is likewise an outlet 134 for the fluid medium which is intended to be connected to the pipe 135. From Figure 4 it will be seen that the shaft 122 has secured to it a gearwheel 136 which meshes with a pinion 137 secured upon a shaft 138 carrying a further fixed pinion 139. The latter engages with a gearwheel 140 secured upon the extension 141 of the output shaft 126 of the hydraulic motor 125A. There is a casing 142 which serves to carry the shaft 138 and which is itself angularly displaceable about the axis of the shafts 122 and 141. The casing 142 is formed with a cam 143 which is so profiled that the lift experienced by the follower 131 is proportional to the angular distance through which the cam may be turned. There is also provided upon the casing a peripheral series of gear teeth 144 which mesh with a pinion 145 secured to the shaft 124.

From the above description it will be understood that if the shaft 122 is turned (with the motor 125A initially inoperative) then the casing 142 will be angularly displaced by virtue of the pinions 137 and 139. Thereby the cam 143 will cause a proportionate lift of the follower 131 and fluid medium will flow in one direction or the other to the hydraulic motor, whereupon the latter will begin to operate accordingly. The extension 141 of the output shaft 126 will thereby be rotated so that the pinion 140 will likewise rotate and tend to return the valve 129 to its zero position by virtue of the cam-follower arrangement. It will be seen that the movement of the casing 142 will be a direct measure of the lag in the hydraulic system and that the shaft 124 will turn in accordance with such lag.

The power amplifier hunter follow-up system described is, in this particular instance, applied to training. It will be understood that a precisely similar system is applied to the elevating correction.

The operation of the system as a whole is similar to that of the system illustrated in Figure 1, the movements of the shafts 116 and 117 being, in this case, proportional to the rates of training and elevating respectively since the adjustments made in the valve boxes 100 and 101 will control the rate of operation of the respective

hydraulic motors 91 and 92 which directly control the elevating and training mechanism. The system of Figure 3 will be observed to have certain advantages over that described with reference to Figure 1, for the reason that a single source of fluid medium, indicated at 95 is all that is necessary to operate the various hydraulic motors. In the previously described system each hydraulic unit is complete with pump and 10 motor.

In the above described systems the use of two control handles has been referred to, one in respect of training and the other for elevating. It will be understood that a single universally adjustable member such as a "joy-stick" control member may be utilised.

What is claimed is:

1. In a fire control system, sighting means, a predictor, input and output motion transmitting members associated with said predictor, gun operating mechanism controlled by the output members of the predictor, hydraulic motors having output connections to said sighting means for imparting training and elevating movements to the sighting means and also having driving connections to the input members of the predictor so as to apply to the predictor measurements of training and elevating displacements of the sighting means, hydraulic fluid pressure generating means supplying said motors, means regulating the supply of hydraulic fluid pressure to said hydraulic motors for selectively controlling the adjustment of the sighting means for training and elevation, and means transmitting to the predictor a measure of the rate of training and elevation applied to said regulating means.

2. In a fire control system, sighting means, a predictor, input and output motion transmitting members associated with said predictor, gun operating mechanism, hydraulic motors having output connections to said sighting means for imparting training and elevating movements to the sighting means and also having driving connections to the input members of the predictor so as to apply to the predictor measurements of training and elevating displacements of the sighting means, pumps supplying the said hydraulic motors, means for selectively adjusting said pumps to control the adjustment of the sighting means for training and elevation, and means transmitting to the predictor a measure of the rate of training and elevation applied to the sighting means via said adjustable pumps, the output members driven from the said predictor being adapted to apply corrections in training and elevation to the gun operating mechanism.

3. In a fire control system, an observing sight, a predictor, gun elevating and training means, a hydraulic swash-plate motor having an output to said sight for adjusting the sight in training, a second swash-plate motor having an output for adjusting the sight in elevation, means transmitting said training and elevating adjustments of the sight to the predictor, swash-plate pumps supplying hydraulic pressure fluid to said motors, means for adjusting the angulation in said swash-plate pumps, means transmitting to the predictor movements proportional to the rate of change of the sight elevating and training adjustments derived from the adjustment of the angulation of said pumps, a hydraulic power amplifier-hunter follow-up system for driving the gun elevating and training means, and outputs from the predictor to said power amplifier system for intro-

ducing thereto the corrections in training and elevation to be applied to the gun.

4. In a fire control system, an observing sight, a predictor, gun elevating and training means, a hydraulic swash-plate motor having an output to said sight for adjusting the sight in training, a second swash-plate motor having an output for adjusting the sight in elevation, means transmitting said training and elevating adjustments of the sight to the predictor, a pump to supply said motors with hydraulic pressure fluid, selectively adjustable valves for controlling the supply of hydraulic pressure fluid to said motors, means transmitting to the predictor movements proportional to the rate of change of the elevating and training adjustments derived from the adjustment of said valves, a power amplifier hunter follow-up system for driving the gun elevating and training means, and outputs from the predictor to said power amplifier system for introducing thereto the corrections in training and elevation to be applied to the gun.

5. In a fire control system, sighting means, a predictor, gun operating mechanism, outputs from said predictor for transmitting corrections in training and elevation to be applied to the gun operating mechanism, a power amplifier follow-up gear for magnifying the said corrections derived from the predictor and for applying them to the gun operating mechanism, a swash-plate pump and motor system and associated power source means for driving the pumping means of said system, means associated with the motor portion of said system for applying to the sighting means adjustments in training and elevation and for transmitting corresponding adjustments to the predictor and means for transmitting to the predictor movements proportional to the rate of change of the elevating and training adjustments of the sighting means.

6. In a fire control system, sighting means, a predictor, gun operating mechanism, outputs from said predictor for transmitting corrections in training and elevation to be applied to the gun operating mechanism, a power amplifier follow-up gear for magnifying the said corrections derived from the predictor and for applying them to the gear, a swash-plate pump and motor system and associated power source means for driving the pumping means of said system, means associated with the motor portion of said system for applying to the sighting means adjustments in training and elevation and for transmitting corresponding adjustments to the predictor, means for transmitting to the predictor movements proportional to the rate of change of the elevating and training adjustments of the sighting means, and a return drive from the power amplifier follow-up gear to the predictor for returning to the predictor compensation for lag in the said gear.

7. In a fire control system, sighting means, a predictor, gun operating mechanism, outputs from said predictor for transmitting corrections in training and elevation to be applied to the gun operating mechanism, a power amplifier follow-up gear for magnifying the said corrections derived from the predictor and for applying them to the gun operating mechanism, a swash-plate pump and motor system and associated power source means for driving the pumping means of said system, means associated with the motor portion of said system for applying to the sighting means adjustments in training and elevation and for transmitting corresponding adjustments to

the predictor, means for transmitting to the predictor movements proportional to the rate of change of the elevating and training adjustments of the sighting means, and means for determining lag correction in the follow-up gear consisting of a member arranged to move with the sensitive input to said gear, a second member arranged to move with the power output from the gear and a connecting mechanism between said members, said connecting mechanism being so constructed and arranged that when said members run in the same direction at the same speed the connecting mechanism has no output while a difference in movement of said members produces a corresponding output from said connecting mechanism whereby the lag of said gear is determined.

8. In a fire control system, sighting means, a predictor, gun operating mechanism, outputs from said predictor for transmitting corrections in training and elevation to be applied to the gun operating mechanism, a power amplifier follow-up gear for magnifying the said corrections derived from the predictor and for applying them to the gun operating mechanism, a hydraulic system having swash-plate pump means and a plurality of hydraulic motor means, associated power source means for driving said pump means, means associated with certain of said hydraulic motor means for applying to the sighting means adjustments in training and elevation and for transmitting corresponding adjustments to the predictor, said adjustment applying means embodying a pair of selectively operable manually controlled valves for controlling the supply of pressure fluid to said last named motor means, and means for transmitting to the predictor movements proportional to the rate of change of adjustment of said valves.

40 9. In a fire control system, sighting means, a predictor, gun elevating and training means, a pair of swash-plate hydraulic motors each having an output to the sighting means for adjusting the sighting means for training and elevation, a pump common to said motors, a power unit driving said pump, a pair of manually controlled valves for regulating the supply of pressure fluid to said motors, connections from said valves to said predictor for transmitting to the predictor movements proportional to the rate of change of the valve positions, means transmitting the training and elevating adjustments of the sighting means to said predictor, a power amplifier hunter follow-up system for driving the gun elevating and training means, and outputs from the predictor to said power amplifier system for introducing thereto the corrections in training and elevation to be applied to the gun elevating and training means.

60 10. In a fire control system, sighting means, a predictor, gun elevating and training means, a pair of swash-plate hydraulic motors each having an output to the sighting means for adjusting the sighting means for training and elevation, a pump common to said motors, a power unit driving said pump, a pair of manually controlled valves for regulating the supply of pressure fluid to said motors, connections from said valves to said predictor for transmitting to the predictor movements proportional to the rate of change of the valve positions, means transmitting the training and elevating adjustments of the sighting means to said predictor, a power amplifier hunter follow-up system for driving the gun elevating and training means, outputs from the pre-

dictor to said power amplifier system for introducing thereto the corrections in training and elevation to be applied to the gun elevating and training means, and means for determining lag correction in the hunter follow-up system consisting of a member arranged to move with the sensitive input to said system, a second member arranged to move with the power output from said system and a connecting mechanism between said members, said connecting mechanism being so constructed and arranged that when said members run in the same direction at the same speed the connecting mechanism has no output while a difference in movement of said members produces a corresponding output from said connecting mechanism whereby the lag of said gear is determined.

11. In a fire control system, an observing sight, a predictor, gun operating mechanism, a first hydraulic swash-plate motor having an output to said sight for adjusting the sight in training, a second hydraulic swash-plate motor having an output for adjusting the sight in elevation, means transmitting said training and elevating adjustments of the sight to the predictor, a hydraulic power amplifier hunter follow-up system for driving the gun operating mechanism, outputs from the predictor to said power amplifier system for introducing thereto the corrections in training and elevation to be applied to the gun operating mechanism, said hydraulic power amplifier hunter follow-up system embodying a pair of swash-plate hydraulic motors, power driven pump means to pump hydraulic fluid to said first, second and third pair of swash-plate hydraulic motors, selectively adjustable means controlling the flow of hydraulic pressure fluid to said first and second swash-plate motors, means transmitting to the predictor movements proportional to the

rate of change of the elevating and training adjustments derived from the adjustment of said selectively adjustable means, a valve controlling the flow of hydraulic pressure fluid to each of said pair of swash-plate motors, an epicyclic gear connecting the input shaft of each of said pair of swash-plate motors to one of the outputs from the predictor, and a cam for actuating each of said valves driven by the associated epicyclic gear, said cams being so constructed that the associated valves are adjusted away from a zero setting in accordance with the difference in the relative positions of said outputs from the predictor and the input shafts of said pair of swash-plate motors.

THOMAS FREDERICK CLARKE,
PERCY WILLIAM COLE,
Executors of the Estate of Maurice Kerr Ingoldby, Deceased.
